SHAFT SEALING DEVICE

Sebastian Karrer, Washington, D. C., and Henry C. Mohlenrich, Baltimore, Md., assignors to Consolidated Gas Electric Light and Power Company of Baltimore, Baltimore, Md., a corporation of Maryland

Application November 4, 1932, Serial No. 641,262

12 Claims. (Cl. 286—11)

This invention relates to shaft sealing devices, and more particularly to devices of this character which are used to seal the shafts of pumps or compressors of refrigeration systems.

It is well known that in refrigeration systems, such as those employing sulphur dioxide as the circulating heat-extracting medium, corrosion of the parts will take place when air and water vapor leak into the system, which corrosion in time will interfere with proper operation of the system. Our investigations have shown that the types of seals or stuffing boxes provided for the shafts of the pumps and compressors of most commercial household refrigerating systems will not prevent the infiltration of air and water vapor when the gas pressure within the compressor or pump is less than the atmospheric pressure outside. We have also found that unless adequate provisions are made for maintaining a liquid filling between the relatively movable bearing surfaces of the seal as well as for lubricating such a seal the rate of infiltration of air and water vapor may become relatively high. Moreover, we have discovered that when such a compressor or pump shaft seal is constructed to effectively prevent leakage of air and water vapor into the refrigerating system it will also render practically negligible the escape of the refrigerating fluid from the system.

It is therefore one of the objects of the present invention to provide a new and improved sealing device for the shaft of a compressor or pump which will not only effectively prevent leakage of fluids or vapor around said shaft into and out of said compressor or pump, but will also afford an adequate supply of lubricant for the cooperating parts of said shaft and seal.

Another object is to provide a novel and efficient sealing device for the shaft of a refrigerator or compressor or pump which can be quickly and easily installed as an accessory in refrigerating systems already in use without requiring any reconstruction of the original mechanism.

A further object is to provide a pump or compressor shaft seal of simple construction which can be economically manufactured and readily installed to provide a highly efficient seal against the ingress and egress of gas and vapor with respect thereto.

Still another object is to provide a novel seal for compressor or pump shafts in which a quantity of sealing liquid can be stored and conserved for relatively long periods of time.

A still further object is to provide as a new article of manufacture a unitary oil reservoir and

sealing device which is capable of being easily installed in the field as an accessory to and to improve the efficiency of the various sealing devices with which the shafts of refrigerator pumps or compressors are originally supplied.

These and other objects will appear more fully upon a consideration of the detailed description of the invention which follows. Although only one embodiment of the present invention is described and illustrated in the accompanying drawing, it is to be expressly understood that this drawing is for the purpose of illustration only and is not to be construed as a definition of the scope of the invention, reference being had for this purpose to the appended claims.

In the drawing, which constitutes a sectional view through the axis of the outer end of the shaft of a compressor or pump showing a shaft sealing device constituting one embodiment of the present invention, 1 represents the shaft of a compressor or pump of any desired type, such as the compressor of a household refrigerating system, said shaft being journaled in a suitable bearing 2 supported in a portion of the compressor casing or housing 3. The outer end of shaft 1 is provided with an extension 4 of reduced diameter which projects outwardly beyond the end of compressor casing 3 and to the end of which is secured a suitable driving element, as a flywheel or driving pulley 5, the latter having a wedged fit 30 with the tapered end of shaft extension 4 and being suitably secured thereon as by a nut 6.

In order to prevent leakage of the refrigerating fluid from within the compressor and infiltration of air and water vapor thereto, a suitable sealing device is provided for the end of the compressor shaft. As shown, a sealing ring 7 of any suitable material is mounted on the movable head 8 of a flexible bellows member 9 and is supported thereby in sealing engagement with the shoulder 10 formed at the junction of shaft extension 4 and the larger portion of shaft 1. Bellows member 9 and its associated sealing ring 7 are housed in a suitable recess 11 formed in the outer end of compressor casing 3, the fixed head of the bellows having an enlarged outwardly extending flange 12 which is fixedly secured in proper position between the outer face of casing 3 and an annular retaining plate 13 which is secured to said casing by a plurality of circumferentially spaced screws or bolts 14. If desired, a sealing gasket 15 of any suitable material may be provided between flange 12 and the face of compressor casing 3. Sealing ring 7 is resiliently urged into sealing engagement with shoulder 10 55

by a suitable coil spring 16 housed within bellows member 9 surrounding shaft extension 4 and exerting its thrust against the inner face of the movable head 8 of the bellows, the other end of said spring seating against the inner portion of annular retaining plate 13.

The seal thus far described is a well known construction now in use on a large number of compressors and pumps of commercial refrigerating systems. While this particular type of seal with stationary sealing bellows has been described in detail to show clearly the application of the present invention, it will be obvious that the invention is equally applicable to other types of seals, as for instance that in which the bellows carrying the sealing member is attached to the shaft and rotates with it.

In the type of seal described, escape of the refrigerating fluid can take place from within the compressor around shaft 1 into the recess 11, between the bearing surfaces of shoulder 10 and sealing ring 7 into the interior of bellows member 9 and out to the atmosphere through the opening in retaining plate 13 around shaft extension 4, while infiltration of air and water vapor from the atmosphere into the interior of the compressor may take place in the opposite direction. In this usual type of seal especially when no oil or other lubricant is provided for the bearing surfaces of shoulder 10 and sealing ring 7, the rates of leakage and infiltration may become relatively high.

In order to prevent such leakage and infiltration, and also to adequately lubricate the bearing surfaces of the seal, the present invention includes a reservoir for a sealing liquid, which is also preferably a lubricant and which reservoir is in communication with the sealing device. Said reservoir may be installed as a unit in the field upon seals of the type just described or it may form a part of the seal as originally provided by the compressor manufacturer. In the form shown, the reservoir comprises a casing 17 to one end of which is suitably secured a flexible wall or diaphragm 18 having a central opening therein which is slightly larger than the diameter of shaft extension 4, the flexibility of said wall or diaphragm being provided in any suitable manner, here shown as by forming thereon in a plurality of concentric circular corrugations 19, while the sealing means also includes means of any suitable construction for preventing leakage of oil between said wall 18 and the shaft 4, here shown as a sealing ring 20 of suitable material secured to the wall 18 around said central opening. While casing 17 may be of any desired shape, dependent upon the construction of the shaft seal to which the reservoir is applied, and said casing may be mounted on the plate 13 in any suitable way, the embodiment illustrated is substantially cylindrical with its interior diameter equal to or slightly larger than the diameter of the circle passing through the outer edges of the heads of screws 14 which hold retaining plate 13 to the compressor housing 3 so that a sliding or aligning fit between the interior of casing 17 and the heads of screws 14 is obtained when the reservoir is moved into place.

In installing the combined lubricating and sealing device in the field, it is necessary only to remove flywheel 5 from the end of shaft extension 4, slide the reservoir and its associated sealing ring over the end of the shaft, and then move casing 17 over the heads of screws 14 and into

engagement with the outer face of annular retaining plate 13. An oil-tight gasket 21 is preferably inserted between plate 13 and the end of casing 17, and the joint formed between said elements is covered with a suitable liquid cement as indicated at 22. A suitable washer 23 and oil-proof gasket 24 are then placed upon shaft extension 4 and moved into engagement with sealing ring 20, and finally flywheel or driving pulley 5 is replaced upon the shaft in engagement with gasket 24 to complete the assembly. When thus assembled, the space enclosed by retaining plate 13, casing 17, flexible wall 18 and the seal comprising sealing ring 20 and its associated elements cooperating with the shaft or the flywheel 15 or driving pulley 5 constitutes a liquid-tight reservoir which communicates with the interior of bellows member 9 through the opening in retaining plate 13 around shaft extension 4. This reservoir is also provided with a suitable filling member 25 through which oil or other suitable sealing liquid 26 is added until the entire seal, including the interior of bellows member 9, is completely full, as shown in the drawing, whereby not only is the bellows kept full of said liquid 25 but the liquid in the bellows is maintained under a head by the liquid in the reservoir. Hence leakage between the bearing surfaces between ring 7 and shoulder 10 is prevented by the liquid filling between said surfaces, while the volume of liquid in the reservoir is sufficient to keep the bellows full and prevent the destruction of the sealing film, notwithstanding the reversals in pressure which occur in the relative values of the interior gas pressure and atmospheric pressure, because the bearing surfaces are flooded at all times. Member 25 is also open to the atmosphere so as to provide a vent for the reservoir.

It will be understood that the dimensions and shapes of the various elements of the lubricating and sealing device will vary for different installations in accordance with the dimensions and shapes of the elements with which they will be installed or the clearance between the inner face 45 of flywheel or driving pulley 5 and the outer face of retaining plate 13. Also, in some refrigerating units the compressor or pump shaft is directly connected with a motor so that no driving pulley or flywheel is used, but it will be understood that the present invention may still be embodied in such a construction by providing or utilizing any suitable means for preventing escape of the lubricant between the wall 18 and the shaft 4.

As previously pointed out, the reservoir is open to the atmosphere, so that any refrigerating fluid which may escape from the compressor past the compressor seal during the time when the refrigerator is defrosting, or when for other reasons the compressor is not operating, will escape directly to the atmosphere, and will not build up a high pressure or eject the sealing liquid. Thus, the pressure tending to force the sealing liquid past the seal between bearing ring 20 and washer 23 is only the hydrostatic pressure due to the height of the liquid 26 within the reservoir. The pressure on the liquid 26 within the reservoir thus being very small, only a slight pressure of bearing ring 20 against washer 23 is necessary to prevent leakage of the liquid at this point. This outward pressure is normally obtained by the resiliency of flexible wall or diaphragm 18, although in the event that this resiliency is not sufficient to provide the pres- 75

sure necessary to maintain a liquid-tight seal between bearing ring 20 and washer 23, a suitable coil spring 27 may be provided inside of the reservoir exerting its thrust against the inner face of flexible wall 18 with its opposite end seating against the outer surface of annular retaining plate 13.

While the invention has thus far been described as adapted for embodiment in an accessory unit 10 to be applied to compressor or pump shafts already in service and equipped with a dry seal of well known construction, it is apparent that it may also be embodied in complete sealing devices to be applied at the time of original assembly of 15 the compressors or pumps. In such event, it would be desirable to modify the construction of the reservoir somewhat, as for example, by decreasing the diameter of cylindrical casing 17 to a dimension less than the diameter of the circle 20 passing through the inner edges of the heads of screws 14 and providing said casing with an outwardly extending flange whereby the reservoir could be securely fastened to retaining plate 13 and the compressor casing 3 by screws 14. Such a 25 modified construction would not be desirable for an accessory to be installed in the field since it would necessitate the removal of screws 14 for its installation and thus afford opportunity for leakage through the joints of the already installed 30 seal.

There is thus provided by the present invention a new and improved sealing device which is particularly well adapted for use on the shafts of pumps or compressors of refrigerating systems, 35 said device not only effectively preventing leakage of fluids and vapors along the shaft into and out of the compressor or pump but also adequately lubricating the cooperating parts of the seal. The illustrated embodiment of the invention 40 constitutes a simply constructed accessory which can be quickly and easily installed on a compressor or pump already in service so as to greatly increase the efficiency of the existing seal, said installation being possible without impairing 45 the existing seal or necessitating removal of the refrigerating fluid from the system. It will be obvious, however, that the invention is not limited to the construction shown in the drawing, but is capable of a variety of mechanical embodiments. 50 For example, any suitable means may be employed for securing the reservoir in its proper position instead of the specific arrangement shown, while other forms of resilient wall may be substituted for the corrugated diaphragm described and illustrated. Also, in some installations a sufficiently tight seal can be obtained between sealing ring 20 and the shaft or the hub of flywheel or 55 driving pulley 5 and washer 23 and gasket 24 may be omitted. Various other changes, which will 60 now appear to those skilled in the art, may be made in the form, details of construction and arrangement of the parts without departing from the spirit of the invention, and reference will therefore be had to the appended claims for a 65 definition of the limits of the invention.

What is claimed is:

1. An accessory to be applied to the shaft of a compressor or pump between the flywheel or driving pulley thereof and an existing seal of the type embodying a sealing ring engaging a shoulder on the shaft and mounted on one end of a flexible bellows member the other end of which is clamped to the compressor or pump casing by a retaining plate secured to said casing, comprising a reservoir having a cylindrical casing closed

at one end by an annular end wall, the opening in said wall being larger than said shaft whereby the reservoir may be placed upon said shaft with its open end secured to said retaining plate and the interior thereof communicating with the interior of said bellows member, means through which said reservoir and the communicating bellows member may be filled with a sealing liquid, and sealing means carried by said end wall and adapted to cooperate with said flywheel or driving pulley to form a fluid-tight joint for preventing leakage of said sealing liquid from the reservoir. 5

2. A sealing device for the shaft of a compressor or pump of the type having a flywheel or driving pulley secured to the end of the shaft which extends outside of the compressor or pump casing, comprising a shoulder formed on said shaft, a sealing ring in engagement with said shoulder, a bellows member surrounding said shaft on one 20 end of which said sealing ring is mounted, a flange secured to the other end of said bellows member, an annular retaining plate secured to the pump or compressor casing, a substantially cylindrical casing surrounding said shaft between said retaining plate and the flywheel or driving pulley with its inner end secured to said plate, an annular end wall closing the outer end of said casing around said shaft, said casing, retaining plate and end wall forming a reservoir for a sealing liquid the interior of which is in communication with the interior of said bellows member, means through which said sealing liquid may be supplied to said reservoir, and a sealing member carried by said end wall and cooperating with 25 the flywheel or driving pulley to form a fluid-tight joint therebetween for preventing leakage of said sealing liquid from the reservoir. 30

3. An accessory adapted to be applied to the shaft of a compressor or pump and to cooperate with an existing sealing device including a sealing ring engaging a shoulder on the shaft and mounted on one end of a bellows member with the other end of said bellows member making a fluid-tight joint with the casing of the compressor or pump, said accessory comprising a reservoir adapted to be detachably mounted about said shaft laterally with respect to the end of said bellows member and without modification of the existing seal with the interior thereof in free communication with the end of the chamber within said bellows member whereby said chamber may be maintained full of said liquid under a head of liquid existing in said reservoir, means through which said reservoir and the communicating bellows member may be filled with a sealing liquid, and sealing means carried by said reservoir and adapted to form a fluid-tight joint for preventing leakage of said sealing liquid from said reservoir along said shaft. 40

4. In a sealing device for the shaft of a compressor or pump, in combination with the shaft and a seal for said shaft including a bellows surrounding the shaft and having a sealing ring engaging an opposed surface to provide relative 45 rotatable cooperating sealing surfaces, means for maintaining said sealing surfaces under a head of sealing liquid comprising a reservoir adapted to surround said shaft with the interior thereof freely in communication with the chamber of 50 said bellows, said reservoir adapted to contain a sealing liquid and to maintain said chamber full of said sealing liquid under a head of liquid existing in said reservoir, means for securing said reservoir to said chamber laterally with respect 55 to said shaft. 60

to the end thereof, and sealing means carried by said reservoir for preventing leakage of the sealing liquid therefrom along the shaft.

5. In a sealing device for the shaft of a compressor or pump, in combination with the shaft and a seal for said shaft including a bellows surrounding the shaft and having a sealing ring engaging an opposed surface to provide relatively rotatable sealing surfaces, means for maintaining 10 said sealing surfaces under a head of sealing liquid comprising a reservoir closed at one end by a resilient end wall apertured to receive the shaft and adapted to surround said shaft with the interior thereof freely in communication with the 15 chamber of said bellows, said reservoir adapted to contain a sealing liquid and to maintain said chamber full of said sealing liquid under a head of liquid existing in said reservoir, means for securing said reservoir to said chamber laterally with respect to the end thereof, and sealing 20 means carried by said resilient end wall for preventing leakage of said sealing liquid from said opening in the end wall of the reservoir.

6. In a sealing device for the shaft of a compressor or pump, in combination with the shaft and a seal for said shaft including a bellows surrounding the shaft and having a sealing ring engaging an opposed surface to provide relatively rotatable sealing surfaces, means for maintaining 30 said sealing surfaces under a head of sealing liquid comprising a reservoir having a flexible end wall apertured to receive the shaft and adapted to surround said shaft with the interior thereof freely in communication with the chamber of said bellows, said reservoir adapted to contain a sealing liquid and to maintain said chamber full of said sealing liquid under a head of liquid existing in said reservoir, means for securing said reservoir to said chamber laterally with respect to 35 the end thereof, sealing means carried by said flexible end wall, and resilient means within said reservoir for urging said sealing means into sealing engagement with means rotating with said shaft to prevent leakage of the sealing liquid from 40 said opening in the end wall of the reservoir.

7. In a sealing device for the shaft of a compressor or pump, an expansible and collapsible chamber surrounding said shaft and having a sealing ring in engagement with an opposed surface to provide relatively rotatable sealing surfaces, and means for supplying a sealing liquid to said sealing surfaces including a reservoir mounted laterally with respect to the end of said chamber and having free communication through 55 the end of said chamber with the interior thereof, said reservoir adapted to contain a sealing liquid and having a vertical radial dimension materially in excess of the radial dimension of said chamber, whereby said reservoir is adapted to maintain said chamber full of sealing liquid under a head of liquid existing in said reservoir, and sealing means carried by said reservoir and acting independently of said sealing ring to prevent leakage of the sealing liquid therefrom along 60 the shaft.

8. In a sealing device for the shaft of a compressor or pump, a resiliently actuated expansible and collapsible chamber surrounding said shaft and having a sealing ring in engagement with an opposed surface to provide relatively rotatable sealing surfaces, and means for supplying a sealing liquid to said sealing surfaces including a reservoir mounted laterally with respect to the end of said chamber and having free 70 communication through the end of said chamber

with the interior thereof, said reservoir adapted to contain a sealing liquid and having a vertical radial dimension materially in excess of the radial dimension of said chamber, whereby said reservoir is adapted to maintain said chamber full of sealing liquid under a head of liquid existing in said reservoir, said reservoir including a resiliently actuated end wall and sealing means carried thereby and acting independently of said resiliently actuated chamber, to prevent leakage 10 of the sealing liquid from said reservoir along said shaft.

9. In a sealing device for the shaft of a compressor or pump, an expansible and collapsible chamber surrounding said shaft and having a sealing ring resiliently urged into engagement with an opposed surface to provide relatively rotatable sealing surfaces and form a gas-tight seal, and means for supplying a sealing liquid to said sealing surfaces including a reservoir mounted laterally with respect to the end of said chamber and having free communication through the end of said chamber with the interior thereof, said reservoir adapted to contain a sealing liquid and having a vertical radial dimension materially in excess of the radial dimension of said chamber, whereby said reservoir is adapted to maintain said chamber full of sealing liquid under a head of liquid existing in said reservoir, said reservoir including a flexible end wall, sealing means carried thereby, and resilient means in said reservoir cooperating with said sealing means and acting independently of said resiliently urged sealing ring to urge said sealing means into contact with means rotating with said shaft and form a liquid-tight seal.

10. In a sealing device for the shaft of a compressor or pump, a bellows surrounding the shaft and having a sealing ring engaging an opposed surface to provide relatively rotatable sealing surfaces, means for maintaining said sealing surfaces under a head of sealing liquid comprising a reservoir of larger diameter than said bellows having an apertured end wall adapted to surround the shaft and its opposite end in open communication with the chamber in said bellows, said reservoir adapted to contain a sealing liquid and to maintain said chamber full of said sealing liquid under a head of liquid existing in said reservoir, means for detachably securing said reservoir to said chamber laterally with respect to the end thereof, sealing means carried by said reservoir for preventing leakage of the sealing liquid therefrom along the shaft, and means for venting the interior of the reservoir to the atmosphere whereby any gas which may leak from the compressor or pump through said chamber and into said reservoir may pass to the atmosphere.

11. In a sealing device for the shaft of a compressor or pump, in combination with the shaft and a seal for said shaft including a bellows surrounding the shaft and having a sealing ring engaging an opposed surface to provide relatively rotatable sealing surfaces, means for maintaining said sealing surfaces under a head of sealing liquid comprising a reservoir closed at one end by an end wall apertured to receive the shaft and adapted to surround said shaft with the interior thereof freely in communication with the chamber of said bellows, said reservoir adapted to contain a sealing liquid and to maintain said chamber full of said sealing liquid under a head of liquid existing in said reservoir, means for detachably securing said reservoir to said chamber laterally with respect to the end thereof, and sealing means car-

ried by said end wall for preventing leakage of said sealing liquid from said opening in the end wall of the reservoir.

12. In a sealing device for the shaft of a compressor or pump, an expansible and collapsible chamber surrounding said shaft and having a sealing ring in engagement with an opposed surface to provide relatively rotatable sealing surfaces, and means for supplying a sealing liquid to said sealing surfaces including a reservoir mounted laterally with respect to the end of said chamber

ber and having free communication through the end of said chamber with the interior thereof, said reservoir adapted to contain a sealing liquid and having a vertical radial dimension materially in excess of the radial dimension of said chamber, whereby said reservoir is adapted to maintain said chamber full of sealing liquid under a head of liquid existing in said reservoir. 5
